UNITED STATES PATENT OFFICE.

LOUIS JOUBERT, OF PARIS, FRANCE.

IMPROVEMENT IN COMBINED KNAPSACK, TENT, AND LITTER.

Specification forming part of Letters Patent No. 39,150, dated July 7, 1863.

To all whom it may concern:

Be it known that I, LOUIS JOUBERT, of Paris, in the Empire of France, have invented a new and Improved Knapsack, Litter, and Tent Combined; and I do hereby declare that the following is a full, clear, and exact description of the same, reference being had to the accompanying drawings, forming a part of this specification, in which—

Figure 1 represents a perspective view of my invention when carried by a man. Fig. 2 is a perspective view of the knapsack partially opened. Fig. 3 is a perspective view of my litter. Fig. 4 is a similar view of my tent. Fig. 5 is a detached elevation of one of the cross-bars with leg of the litter.

Similar letters of reference in the several views indicate corresponding parts.

The object of this invention is to combine all the elements necessary to make a litter or one-half of a tent with a knapsack in such a manner that the same can be conveniently carried by a soldier, giving him the opportunity to provide the means for carrying a wounded or sick comrade from the battle-field or to shelter himself against the sudden changes of the weather.

To enable others skilled in the art to make and use my invention, I will proceed to describe it with reference to the drawings.

A represents a knapsack made in the ordinary shape and provided with shoulder-straps *a* in the usual manner.

The body of my knapsack consists of a wooden case, which is covered with seal-skin or any other suitable material. The covering opens on the inside and on the outside of the case, and by raising the outside lid, B, access can be had to the interior of the knapsack. Said lid is secured by means of straps and buckles in the ordinary way. The inside lid, C, which is situated next to the back of the man carrying the knapsack, is also fastened by means of straps and rolled up between it and the wooden case in the canvas D, which serves as the bottom of the litter, or as one-half of a tent-covering, as the case may be.

E E' are the poles or sticks which support the canvas when the same is to be used as a litter or as a tent. The sticks are united in the middle by a bayonet-fastening, *b*, and when

rigged up for a litter they pass through loops *d* in the edges of the canvas, and their ends are inserted into rings *c*, attached to the cross-bars F. These cross-bars are provided with legs *e*, which can be turned up on the sides of the cross-bars, as clearly shown in Fig. 1, or turned down, as shown in Figs. 3 and 5. Straps *f*, attached to the middle of the cross-bars, are passed through holes *g* in the ends of the canvas, and by tightening these belts the canvas is stretched.

In order to support the head of the person laying on the litter, the canvas D may be strapped to the lower edge of the knapsack, and the latter secured in an inclined position to one of the cross-bars F by means of straps *h h'*, which are secured to its sides. Two of these straps may be passed through rings *i* at the ends of the cross-bar and the other two round the poles E E' inside the cross-bar, as clearly shown in Fig. 3 of the drawings. At the same time the inside lid, C, may be turned up and supported by stays *j*, so as to form a shelter for the head of the person lying on the litter. The case or body of the knapsack forms a pillow, and the inclination of the same may be varied by means of the straps *h h'*.

When used as a tent, the canvas D has to be detached from the knapsack, and each canvas forms one-half of a tent. The poles E E' are rammed into the ground, and the canvas is stretched over them, as shown in Fig. 4. While on the march, or when not used, the canvas is rolled up and secured under the inside lid, C, and the poles and cross-bars can either be strapped to the sides and top of one knapsack, or they may be divided between two or more men. The straps *h h'* on the sides and the straps *k k'* on the top serve to retain the poles, as shown in Fig. 1 of the drawings.

My combined knapsack, litter, and tent is of the greatest advantage for an army in the field. It will enable two men to carry a wounded comrade from the battle-field and leave him in a convenient position, whereas in ordinary cases and without my litter from four to six men will leave the ranks if they see one of their comrades fall, and the ranks will thereby be thinned in a very embarrassing manner; and, furthermore, the litter will be a comfortable resting-place for a wounded man, and, if

desired, by combining two pieces of canvas a tent can be put up at any moment.

Having thus fully described my invention, what I claim as new, and desire to secure by Letters Patent, is—

The arrangement of the knapsack A, with straps h h' k k' , poles E E', cross-bars F, with hinged legs e', straps f, and canvas D, all com-

bined and operating in the manner and for the purpose substantially as herein shown and described.

LOUIS JOUBERT.
